FOLDING IRONING BOARD

John G. Wernli, South Pasadena, Calif.

Application January 9, 1939, Serial No. 250,062

2 Claims. (Cl. 38—127)

In my Patent No. 1,973,832 dated September 18, 1934, I have shown an ironing board having legs which support the board in horizontal position when in use and which are foldable against the under side of the board, so that the board will occupy small space, when not in use. The present invention embodies a cabinet for housing the board with connections between the board and the cabinet whereby the board may be easily folded in the cabinet or unfolded for use while still connected to the cabinet, or it may be readily detached from the cabinet for use in some other room or place than the one in which the cabinet may be situated. When the legs are unfolded and the board is in horizontal position, the board is supported entirely by the legs, whether it be connected to the cabinet or detached therefrom.

In the accompanying drawings—

Fig. 1 is a front view of the cabinet with the ironing board folded within it, the door of the cabinet being shown in open position, partly broken away;

Fig. 2 is a vertical section through the cabinet and ironing board on the line 2—2 of Fig. 1, showing the ironing board swung outwardly about its pivotal connection to the cabinet slide, with the legs of the board unfolded;

Fig. 3 is a similar view through the ironing board and the lower part of the cabinet, showing the ironing board in horizontal position and supported by its legs;

Fig. 4 is a transverse section through the cabinet and ironing board, on the line 4—4 of Fig. 1;

Fig. 5 is a perspective view of a portion of one of the side bars of the slide and the fitting thereon to which the ironing board pivots;

Fig. 6 is a perspective view showing a portion of the ironing board with part of one of the pivot rods attached, and,

Fig. 7 is a similar view showing one of the pivot rods in engagement with one of the guide-bars of the slide, the latter and one of the fittings thereon being shown in section.

Referring to the drawings, A represents a cabinet of suitable form and size for containing the folded ironing board B and its supporting structure. The cabinet body is composed of a back 1, parallel sides 2, 3, a top 4 and a bottom 5, and its side pieces extend below the bottom, forming supporting legs 2^a and 3^a. A door a, hinged to the side 3 and extending from the top piece to the bottom piece, is provided for closing the cabinet. Internal guide-grooves 6 and 7 are formed in the lower halves of the sides 2 and 3, respectively, of the cabinet body, these grooves

extending upwardly from the bottom piece 5 and adapted to receive the side-bars 8 and 9 of a sliding frame s. This frame consists of the side-bars and diagonal metal braces 10 and 11, pivoted together at their central portions, and each connecting the lower end of one bar with the opposite bar near the upper end of the latter. On the inner faces of the guide-bars, near their upper ends, are secured metal plates 12, one of which is shown in detail in Fig. 5 secured to the guide-bar 9. Each plate has an opening 12^a registering with a perforation 13 in the upper end of the guide-bar to which it is attached, as shown in Fig. 7, and it also has a horizontal flange 12^b at its lower end and a vertical flange 12^c at its upper end, at the rear of the guide-bar, these flanges forming stops for the ironing board, as hereinafter described. The ironing board and its supporting means are in all substantial respects the same as shown in my Patent No. 1,973,832, but at the rear end of the board, and on its underside, I provide means for readily attaching it pivotally to the slide s so that it may fold within the cabinet. A metal strip 14 is secured to the under side of the board at its rear or broader end, and extends across the board. A circular disc 15 is centrally pivoted on this strip and to this disc, at diametrically opposite points, are pivotally connected metal rods 16 and 17. The rods extend into guides 18 secured to the end portions of the metal strip. By turning the disc 15 in one direction, the rods may be projected through the openings 12^a in the plates 12 connected to the guide-bars 8 and 9 and by turning the disc 15 in the opposite direction, the rods may be withdrawn from these perforations. The disc is provided with a suitable handle 15^a by means of which it may be turned. The disc has locking features, not necessary to describe, for holding it in either position of adjustment.

To attach the ironing board to the slide, the board is raised to a vertical or nearly vertical position, as shown in Fig. 2, and its larger or rear end is lowered onto the flanges 12^b of the metal plates 12. The flanges 12^c on the plates prevent the board from slipping backward on the supporting flanges while the board is being lowered onto the latter. When the board is properly positioned on the flanges, the disc 15 (Figs. 1, 4 and 7) is turned in the proper direction to project the pivot rods 16 and 17 through the openings 12^a in the plates 12 and the ironing board is then pivotally connected to the slide s. To disconnect the board from the slide, it is merely necessary to rotate the disc 15 in the

proper direction to withdraw the pivot rods 16 and 17 from the openings in the plates 12.

In Figs. 2 and 3, the supporting legs 20 and 21 of the ironing board are shown unfolded. To rock the board from the position shown in Fig. 2 to that shown in Fig. 3, the board is lifted and at the same time turned about its axis until the legs 20 and 21 are in engagement with the floor. The board will then be supported entirely by the legs and the slide will be supported by the board in the upper position shown in Fig. 3. To fold the board in the cabinet after it has been in the position for use (Fig. 3), the forward end of the board is raised and as the weight is taken off of the legs, the slide descends and finally rests upon the bottom 5 of the cabinet and supports the board as it is rocked to the position shown in Fig. 1 and in that position, the legs are folded against the under side of the board and the board is held in the vertical position by spring latches 22 which are attached to the inner sides of the cabinet and frictionally engage the edges of the board.

The cabinet as well as the ironing board are light in weight and portable; but it may be desirable at times to use the ironing board in rooms or places other than that in which the cabinet is situated, and, when this is the case, all the operator has to do is to turn the disc 15 clockwise, in Fig. 1, to disconnect the pivot rods from the slide, and the board can then be removed from the cabinet and set up for use by unfolding its supporting legs.

The ironing board and its folding supports are fully described in my patent hereinbefore referred to but may herein be briefly described. The ironing board has a fitting 23 on its under side, near its rear end, to which a pair of rear legs 20 are pivotally connected, these legs adapted to stand vertically when unfolded, as shown in Fig. 3 and to fold against the under side of the board, as illustrated in Fig. 1. The rear legs are connected by diagonally crossed braces 24 to a fitting 25 at the rear of the pivotal axis of the legs 20. A diagonal leg 21 is pivotally connected to the fitting 25, this leg consisting of two strips 21^a which converge toward the forward end of the board and are suitably connected together at the latter end. A pair of links 26 of equal length are pivotally connected to the central portion of the leg 21 and the upper ends of these links are pivotally connected to the lower ends of links 27, which latter are pivoted at their upper ends to a fitting 28 attached to the under side of the ironing board. The links 26 and 27 constitute folding struts for supporting the forward end portion of the board. Braces 29 pivotally connected to the rear legs 20 extend forwardly and are connected to the pivot pins 30 of the struts. A toggle connection 31-32 extends from the pivot pins 30 of the struts forwardly and upwardly to a suitable fitting 33 on the under side of the board. A cross-piece 32^a forms a stop on the toggle and a hand-piece by which the toggle can be moved.

To fold the board and its supports in the cabinet, the board is rocked upwardly about its connection with the slide, causing the slide to move downwardly to the bottom of the cabinet, 5 and in this position the end of the board rests on the slide. The toggle 31-32 is then broken upwardly by pulling on the hand-piece 32^a, which releases the lock on the struts 26-27 and the braces 29, and by then holding the board against 10 the back of the cabinet and swinging the legs 20 upwardly, all of the parts will fold against the under side of the ironing board, as shown in Fig. 1. To unfold the board and its supporting members, the board can be held against movement in 15 its upright position in the cabinet with one hand, while the diagonal leg 21 is swung away from the board a short distance, which partly unfolds the toggle members and makes the hand-piece 32^a accessible, and then by bearing on the hand-piece to straighten the toggle members, the parts assume the positions shown in Fig. 2, and the board is then swung to the horizontal position shown in Fig. 3, wherein it is supported by 20 its supporting structure independently of the cabinet.

What I claim is:

1. The combination with an ironing board and a cabinet adapted to contain the board when the latter is in vertical position, said board having 25 folding legs adapted to support it independently of the cabinet, of a vertically movable slide in the lower part of the cabinet, and means for detachably connecting the board to the slide comprising perforated fittings arranged at opposite sides 30 of the slide near its upper end, said fittings having parts below the perforations upon which the rear end of the board may rest while the board is being placed in the cabinet, a pair of pivot rods mounted on the board near its rear 35 end and extending transversely of the board, and means for moving said rods endwise in opposite directions into or out of the perforations in said fittings to connect the board to or disconnect it from the slide.

2. The combination with an ironing board and a cabinet adapted to contain the board when the latter is in vertical position, said board having 40 folding legs adapted to support it independently of the cabinet, of a vertically movable slide in the lower part of the cabinet, and means for detachably connecting the board to the slide comprising perforated fittings arranged at opposite sides 45 of the slide near its upper end, said fittings having parts below the perforations upon which the rear end of the board may rest while the board is being placed in the cabinet, a pair of pivot rods mounted on the board near its rear end and extending transversely of the board, and means for moving said rods endwise in opposite directions into or out of the perforations in said fittings to connect the board to or disconnect it from the slide.

3. The combination with an ironing board and a cabinet adapted to contain the board when the latter is in vertical position, said board having 50 folding legs adapted to support it independently of the cabinet, of a vertically movable slide in the lower part of the cabinet, and means for detachably connecting the board to the slide comprising perforated fittings arranged at opposite sides 55 of the slide near its upper end, said fittings having parts below the perforations upon which the rear end of the board may rest while the board is being placed in the cabinet and parts higher than the perforations for guiding the board, a pair of pivot rods mounted on the board near its rear end and extending transversely of the board, and means for moving said rods endwise in opposite directions into or out of the perforations in said fittings to connect the board to or disconnect it from the slide.

4. The combination with an ironing board and a cabinet adapted to contain the board when the latter is in vertical position, said board having 60 folding legs adapted to support it independently of the cabinet, of a vertically movable slide in the lower part of the cabinet, and means for detachably connecting the board to the slide comprising perforated fittings arranged at opposite sides 65 of the slide near its upper end, said fittings having parts below the perforations upon which the rear end of the board may rest while the board is being placed in the cabinet and parts higher than the perforations for guiding the board, a pair of pivot rods mounted on the board near its rear end and extending transversely of the board, and means for moving said rods endwise in opposite directions into or out of the perforations in said fittings to connect the board to or disconnect it from the slide.
